UNITED STATES PATENT OFFICE.

JOHN BAGNALL, OF VICTORIA, BRITISH COLUMBIA.

DESIGN FOR A BLACK OR SHARP KEY FOR KEY-BOARD MUSICAL INSTRUMENTS.

Specification forming part of Design No. **11,360**, dated August 26, 1879; application filed July 24, 1879.
[Term of patent 3½ years.]

To all whom it may concern:

Be it known that I, JOHN BAGNALL, of Victoria, in the county of Victoria, British Columbia, have invented a new and original Design for the Black or Sharp Keys of Key-Board Instruments, of which the following is a specification.

The nature of my design is fully represented in the accompanying drawings, to which reference is made, and in which—

Figure 1 is a top view of a portion of a key-board, in which my design is illustrated. Fig. 2 is a section of the same, taken through the line *x x*, Fig. 1, and showing the keys in side view.

Similar letters of reference indicate corresponding parts.

A represents the white keys of a piano, organ, or other key-board instrument. B are the black or sharp keys of the instrument, which are arranged in connection with the white keys A in the usual way. The upper surface of the black keys B incline downward slightly from their forward ends to their middle parts, and from their middle parts they incline downward toward their rear ends with

a steeper inclination. Near their rear ends the downward inclination passes gradually to a level, and the upper edges of their rear ends are rounded off, as shown in Fig. 2.

This form of key is more ornamental than the ordinary flat key, and also has the further advantage of inducing a learner to hold the fingers in a curved position when striking the keys, and being more agreeable to a finished performer.

What I claim as my invention is—

The design for a black or sharp key of a key-board instrument of the configuration described, consisting of the upper surface inclined downward slightly from the forward end to the middle part, then downward with a sharper inclination from the middle part toward the rear end, and gradually to a level near the rear end, and the upper edge of the rear end rounded off, substantially as shown in the accompanying illustration.

JOHN BAGNALL.
